UNITED STATES PATENT OFFICE.

EUGENE ORA DANIELS, OF TOLEDO, OHIO.

HEATING STOVE OR FURNACE.

SPECIFICATION forming part of Letters Patent No. 767,738, dated August 16, 1904.

Application filed February 13, 1904. Serial No. 193,364. (No model.)

To all whom it may concern:

Be it known that I, EUGENE ORA DANIELS, a citizen of the United States, and a resident of Toledo, in the county of Lucas and State of Ohio, have invented certain new and useful Improvements in Heating Stoves or Furnaces; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to what are known as "hot-air" stoves or furnaces in which the air is drawn over heated surfaces and then discharged while at a high temperature through suitable outlet-flues to the surrounding atmosphere or into pipes leading to the rooms to be heated.

The object of my invention is to provide a novel construction of heating apparatus of the above class whereby the radiating-surface and heating capacity may be materially increased without interfering with the draft or requiring additional fuel; and it consists in a novel arrangement of numerous air-passages in the interior of the stove or furnace, into which cool air is drawn and then delivered into the room in a highly-heated condition, and also in the arrangement of the passages for conducting the smoke, gas, and other products of combustion around these various air-passages in such manner that substantially all of the heat of combustion is taken up by said air-passages before the smoke, &c., pass up the flue to the chimney.

Other objects of my invention will be apparent as the same is hereinafter more fully described.

The invention is fully described in the following specification, of which the accompanying drawings form a part, in which—

Figure 1 is a central vertical sectional view of a stove embodying my invention. Fig. 2 is a plan view of one of the sections of air-passages; and Fig. 3 is a modified construction of my invention, showing the same as embodied in a furnace.

Referring to the drawings, A represents the base or ash-pit of a stove embodying my invention, which has the damper or draft-door *a* provided in its front portion to provide for the removal of ashes and the feeding of air from the atmosphere into the fire-pot B through the grate *b*, both of which are supported by the inwardly flanged or converging portion of the ash-pit A.

An opening *c* is provided through the base A to the atmosphere and communicates with the central cold-air duct C, which extends longitudinally entirely through the stove and is adapted to be supported upon a flanged seat provided at the edge of said opening or in any other suitable manner.

A door *b'* is provided in the front of the fire-pot B to enable fuel to be fed to the fire, should coal or wood be used, or to enable the gas-burner D, which I have shown as encircling the cold-air duct C, to be lighted.

In order to direct the course of the flame and products of combustion arising from the fire and cause the same to be deflected alternately against the outer casing E and the casing of the cold-air duct C as it ascends to find an exit from the upper portion of the stove to the chimney, I provide the baffle-plates E', arranged around the cold-air duct C one on the top of the other, the first being seated on an annular flange *e*, provided on the casing of the duct C at a desired distance above the burner D and having its inner edge flush with the outer casing E of the stove, thus leaving a flue or space between its inner edge and the casing of the duct C for the flame and smoke to pass through. The number of these alternately-arranged baffle-plates E' is mainly determined by the size of the stove and the distance between the fire-pot B and the radiating flues or air-passages F. I have shown three sets of these radiating air-passages, the same being designated F, F', and F'', through which the air that is taken in at the bottom of the stove through the duct C is required to pass prior to its being expelled from the stove.

into the room. The arrangement of the said air-passages is such that the radiating flues of one series are disposed in vertical alinement with the openings between the flues of the adjacent series, so that the products of combustion ascending from the fire are continually impeded and caused to pass in and out between said flues until they have reached the top of the stove, where they pass out to the chimney.

Projecting outwardly from the casing E of the stove are the annular flanges or horizontally-extended portions ffff, whose outer edges are connected by strips of sheet metal or other suitable material to form the encircling drums G and G', the former being adapted to inclose the external mouths of the air-passages F and F' and the latter being similarly arranged with reference to the air-passages F''. A removable lid g is seated on a flange or other projection provided in the air-duct C between the internal mouths of the flues F and F' and causes the air taken in through said duct C to be directed through the radiating flues F into the drum G, whence it is compelled to find an exit through the flues F' back into the central air-duct C above the lid g. The air-duct C is again stoppered at a point above the flues F'' by the removable lid h, and the air, which by this time has become highly heated, is forced through the flues F'' into the drum G', from which it is evenly distributed to the surrounding atmosphere through the multiplicity of apertures i, provided in the casing thereof.

While I have shown the stove embodying my invention as being provided with the drum G for causing the air taken in through the cold-air duct to be passed a number of times through the path of the smoke and flames arising from the fire and with the drum G' for distributing the heated air to the atmosphere, it will be apparent that the lid g may be removed from the air-duct C and said drums G and G' omitted, thereby enabling the heated air to have an unimpeded way through said duct until it reaches the lid h and is radiated through the series of flues F, F', and F'' directly into the surrounding atmosphere. As the upper end of the air-duct C, which terminates immediately under the cap H, is left open, the lid h may be removed therefrom, and thus permit a greater portion of the heated air, which had theretofore found an exit through the radiating air-passages, to pass through said open portion. The advantages to be derived from this feature of my stove are readily apparent, inasmuch as a greater or less heat can be expelled through the top of the duct C by the removal or insertion of the lid h, thus greatly facilitating the cooking of articles thereon.

The usual exit-flue I is provided in the upper portion of the stove, through which the smoke and gases arising from the fire are permitted to escape to the chimney.

It will be noticed by reference to the drawings that I have shown the stove embodying my invention as comprising a series of sections, each of which, with the exception of the top piece and the section immediately 70 above the fire-pot, have the upper edges of their outer and inner casings E and C annularly grooved, as shown in j, to receive the lower edges j' of the next succeeding section, thus adapting the contiguous edges of said 75 sections to be matched and tightly joined. It will be apparent that by this construction the baffle-plates E' may be extended to any desired height and as many of the radiating sections F, F', F'' used as the space to be 80 heated may require. I do not, however, wish to confine myself to this construction, as the heating qualities of my stove would be equally efficient were the same made in any other suitable form or manner so long as the main 85 features of construction are retained.

By reason of the arrangement of the parts comprising my invention the products of combustion that ascend from the fire and seek an exit from the stove through the flue I are 90 first caught by the baffle-plates E' and thrown alternately against the casing of the stove and the casing of the air-duct C, thus further heating the air that has been taken in through the opening c and partially heated by passing through the fire-pot B and causing a considerable quantity of heat to be radiated into the room from the lower portion of the stove. After the products of combustion have passed the baffle-plates E' they are successively baf- 100 fled and circulated among the air-passages F, F', and F'', thus heating the air passing therethrough to a very high temperature before being expelled into the room.

The stove comprising my invention can be 105 readily adapted for use as a furnace by inclosing the same within an outer casing which is connected by pipes with the rooms to be heated, as shown in Fig. 3. In this modified construction 1 represents the central air-duct, 110 which takes its supply of air from a chamber 2, leading to the atmosphere; 3, the combustion-chamber, in which are mounted the baffle-plates 4; 5, 6, and 7, the series of flues radiating from the air-duct 1; 8, the drum, 115 with which the flues 5 and 6 communicate; 9, the hot-air-distributing drum, which may be eliminated, if desired, and 10 the outer casing of the furnace, by means of which the heated air is confined and caused to be expelled to 120 the rooms to be heated through a series of radiating pipes 11. The passage of the air through the central duct 1 is impeded and caused to be directed through the flues radiating therefrom by means of the damper 12 and 125 sliding lid 13, which are controlled from without the furnace by means of the rods 14 and 15, respectively.

It is obvious that such changes in the form, proportion, and minor details of construction 130

of the parts as fairly fall within the scope of my invention may be made without departing from the spirit or sacrificing any of the advantages thereof.

5 Having thus described my invention, what I claim as new, and desire to secure by Letters Patent, is—

1. In a heating stove or furnace, a vertically-disposed air-duct having an air-intake, 10 a plurality of flues communicating with said air-duct and extending transversely of the stove or furnace, a portion of which flues are adapted to take the air from said conduit and the others to return it thereto, and means for 15 permitting the returned air to escape from the stove or furnace.

2. In a heating stove or furnace, an air-duct having an opening to the atmosphere through the bottom of said stove or furnace and extending 20 through the fire-pot and combustion-chamber thereof, a series of flues radiating from said duct, one or more partitions in said duct between a portion of said flues, connection 25 between the external mouths of said di-

vided flues for causing the heated air to be returned to said duct preparatory to its being finally expelled from said stove or furnace.

3. In a heating stove or furnace, an air-duct disposed vertically through and having its 30 air-intake at the lower portion of said duct, a series of flues radiating from said duct, a drum surrounding the casing of said stove or furnace adapted to inclose the external mouths of said flues, a second series of flues radiating 35 from said duct and communicating with the atmosphere, and means in said duct for diverting the heated air therefrom to said drum.

4. In a heating apparatus, a vertical air-duct disposed centrally therethrough, a series of 40 flues radiating from said duct, a drum surrounding said apparatus and inclosing the external mouths of said flues, means for directing the heated air from said duct to said drum, a second series of flues leading from said duct, 45 and a perforated air-distributing drum inclosing the mouths of said second set of flues.

5. In a heating apparatus of the class described, an air-chamber extending substantially therethrough and having an air-intake 50 opening at its lower portion, means associated with said chamber for causing the air therein to transversely traverse the heating-chamber of said apparatus a number of times, and means

for expelling the heated air from said chamber after it has returned thereto.

55

6. In a heating stove or furnace, an air-chamber extending longitudinally thereof and having each end open to the atmosphere, a series of flues radiating therefrom and terminating exteriorly of the combustion-chamber 60 of said stove or furnace, a series of baffle-plates above the fire-pot without said chamber adapted to alternately deflect the heat and flames against the wall of said chamber and the casing of said stove or furnace, and means for 65 causing the heated air to be expelled either through said flues or the end of said chamber.

7. In a heating stove or furnace, an air-chamber vertically disposed therein having an air-intake opening at its lower end, a series of 70 flues radiating from said chamber, means for causing the air in said chamber to be deflected through a portion of said tubes, means for causing said air to be returned to said chamber through the other portion of said flues, and 75 means for expelling said returned air to the atmosphere.

8. In a heating stove or furnace, a centrally-disposed vertical air-duct extending therethrough, a series of flues radiating from said 80 duct, a drum inclosing the external mouths of said flues, a partition for directing the air in said duct through a portion of said flues and returning it through the others, an air-distributing drum, a series of flues leading thereto from said chamber, and a series of baffle-plates above the fire-pot without said duct, for 85 the purpose described.

9. A heating stove or furnace comprising, in 90 separate pieces, an ash-pit, a fire-pot, an air-duct extending vertically through said parts, an outer casing, a heat-baffling section, a series of sections forming a continuation of said air-duct and casing and having flues radiating from said duct, and a top section, the said parts having 95 their contiguous edges so formed as to be matched and form tight joints, substantially as described.

In testimony whereof I have hereunto signed my name to this specification in the presence of 100 two subscribing witnesses.
